UNITED STATES PATENT OFFICE.

SYDNIA C. RENNER, OF LANSING, MICHIGAN.

DESIGN FOR A CHOPPING-KNIFE.

SPECIFICATION forming part of Design No. 28,608, dated May 10, 1898.

Application filed March 19, 1898. Serial No. 674,534. Term of patent 7 years.

To all whom it may concern:

Be it known that I, SYDNIA C. RENNER, a citizen of the United States, residing at Lansing, in the county of Ingham, State of Michigan, have invented a certain new and original Design for a Chopping-Knife, of which the following is a specification, reference being had therein to the accompanying drawing.

The drawing illustrates a perspective of the chopping-knife embodying the new design.

As shown in the drawing, the leading or material feature of the design consists of the conical walls A, merged at their upper portion into a convex top B. The conical walls A are provided with beads C, extending

around the same, and with open-work D, extending parallel with the beads C. The lower edge of the conical walls is provided with a bevel E, and the top or apex of the convex top B is flattened, as shown at F.

Having described the design, what I believe to be new and claim is—

A design for a chopping-knife substantially as herein shown and described. 25

In testimony whereof I affix my signature in presence of two witnesses.

SYDNIA C. RENNER.
